UNITED STATES PATENT OFFICE.

JOHN CONOLLY, OF ALDAN, PENNSYLVANIA, ASSIGNOR OF ONE-HALF TO PATRICK J. McDEVITT, OF PHILADELPHIA, PENNSYLVANIA.

GAME-BOARD.

No. 921,366.

Specification of Letters Patent.

Patented May 11, 1909.

Application filed August 4, 1908. Serial No. 446,855.

To all whom it may concern:

Be it known that I, JOHN CONOLLY, a citizen of the United States, residing at Aldan, in the county of Delaware, State of Pennsylvania, have invented a new and useful Game-Board, of which the following is a specification.

My invention consists of a game board comprising a table, which is provided with 10 pockets, into either of which a ball is adapted to be directed by being bounced on the bed or field of the table to the desired pocket, thus scoring or counting for the player, provision being made for receiving the unpocketed 15 ball in a forfeit chamber, returning it to the foot of the board, where it may be replayed, or causing it to escape from the forfeit chamber, when it will be counted out-of-play, as hereinafter more fully described.

For the purpose of explaining the invention, the accompanying drawing illustrates a satisfactory reduction of the same to practice, but the important instrumentalities thereof may be varied, and so it is to be understood that the invention is not limited 25 to the specific arrangement and organization shown and described.

Figure 1 represents a perspective view of a game board embodying my invention. 30 Fig. 2 represents a longitudinal vertical section thereof.

Similar letters of reference indicate corresponding parts in the figures.

Referring to the drawings:—A designates 35 a board of the form of a table, on the sides and an end of the bed of which are channels B, B', which are in communication with the head end C of the table, as at D, D, said bed and channels being slanting toward the 40 foot of the table.

E designates a head board, the same being connected at its lower end with the sides of the top of the table by the pivots F, whereby the board may be tilted and the angle of 45 the same may be varied. On the front face of the head board are pockets G, which are secured thereto in any suitable manner, it being noticed that in playing the game, a ball is thrown over and against the bed of 50 the table in such a manner that it will bounce thereon and be directed to either of the pockets G and enter the same, thus counting for the player, it being evident that as the angle of the head board may be 55 varied, provision is made for rendering it

more or less difficult to pocket a ball. In order to hold the head board in its adjusted angular position, there is pivotally secured to the same the braces H, which are adapted to be secured to the sides of the table top by 60 the screws J, which pass through slots in said braces into said sides, the effect of which is evident.

On the bed of the table in front of the board E, there is the barrier K, which is 65 composed of a block or piece of suitable material having its upper face inclined in reverse directions forming a ridge and extending from side to side of said bed, it having secured to its rear portion a series 70 of spaced-apart vertical divisions forming chambers L, which are in communication with the head end C of the bed of the table. The pockets G and chambers L are numbered in accordance with the rules of the game, it 75 being seen that when a ball is pocketed, if the pocket is of the same number as the ball it will count double, but if the pocket and the ball are of different numbers, the count will be that of the pocket. Should a ball, 80 fail to be pocketed, it may drop on the head end C of the bed of the table, and so roll to the right or left and enter either of the channels B, by which it will be directed into the channel B', which means that such ball does 85 not count or score, but may be re-used. The ball may, however, lodge in one of the chambers L, which constitutes a forfeit or loss to the player of the number of said chamber, but the ball may receive such im- 90 petus in entering one of said chambers L that it will roll over the ridge of the barrier K to the main field of the bed, and so reach the foot end of the latter, when it is out-of-play, and does not count. Of course, other rules 95 of playing the game may be established, without departing from the nature of the invention involved.

On the sides of the head end of the top of the table, are guards M, and on the head 100 board is the guard M', which overhangs the pockets G, by which provision a ball, if thrown laterally or too high, is prevented from escaping at the sides and top of the table at the head thereof, and is caused to return to the bed, where it may take the usual course. The guards M, M' are made of netting, but other suitable pliable material may be employed, the same readily yielding to the hand in inserting the latter into an adja- 105 110

cent pocket to remove a ball therefrom. Each of the frames of the guards M is formed of angular members, and each is pivoted at one end as at P to the table top, whereby the 5 guards may be tilted more or less to the front or rear according to requirements, while the other end is adapted to enter eyes Q on the top, so as to retain the guard in upright position in either of its adjusted positions, while on removing the frame from said 10 eyes the frame may be readily swung on its pivot and the guard thus moved to the desired position. The top guard M' is formed of vertical and horizontal sections, connected 15 by hinged or pivotal joints, the vertical section having the side members of its frame adapted to be fitted slidably and frictionally in eyes R on the head board E, whereby the guard may be retained on the latter and vertically adjusted thereon. The horizontal section, when in operative position, may be sustained on the frames of the side guards, and when not required for use folded backward on the vertical section and both sections removed from the head board when so required.

The barrier K is detachable from the bed and may be adjusted nearer to or farther from the head board according to requirements, and in some cases, the game may be played without the same.

Having thus described my invention, what I claim as new and desire to secure by Letters Patent, is:—

35 1. A game board provided with a head pivoted thereto and having pockets, and means pivotally connected with the head and adjustably with the board for holding and bracing the head in adjusted inclined positions and chambers adjacent to and open toward said head.

2. A game board provided with a head with pockets thereon and forfeit chambers on the bed of the board in front of said pockets, 45 there being entrances to said chambers from

the head end of the board and side passages adjacent the outermost chambers.

3. A game board provided with a head with pockets thereon, chambers on the bed of the board in front of said pockets, and a barrier on the bed of the board in front of the chambers, said barrier having an inclined face which forms the end wall of said chambers, there being entrances to said chambers from the head end of the board. 55

4. A game board provided with a head with pockets thereon, forfeit chambers on the bed of the board in front of said pockets, and an oppositely inclined barrier on said bed in front of said chambers. 60

5. A game board provided with a head rising therefrom, pockets on said head, and a pivoted ball guard on the board overhanging said pockets.

6. A game board provided with a head 65 rising therefrom, pockets on said head, an oppositely inclined barrier in front of the said head a ball guard on the board around said pockets, and movable means for holding said guard in position. 70

7. A game board having a head rising therefrom, a horizontal guard overhanging the top of said head, vertical members with which said guard is pivotally connected, and means on said head adapted for attachment 75 of said members thereto and retaining said guard in position.

8. A game board having a head rising therefrom, a guard at the side of said head, a frame carrying said guard, and a sustaining 80 device for the frame of said guard, said frame being composed of members, one of which is pivotally connected with the board and the other member is movably fitted in said sustaining device.

JOHN CONOLLY.
